UNITED STATES PATENT OFFICE.

BENJAMIN F. AUGUSTINE, OF BUFFALO, NEW YORK.

ROTARY EXPLOSION-ENGINE.

1,199,229.

Specification of Letters Patent. Patented Sept. 26, 1916.

Application filed July 29, 1912. Serial No. 712,136.

To all whom it may concern:

Be it known that I, BENJAMIN F. AUGUSTINE, a citizen of the United States, residing at Buffalo, in the county of Erie and 5 State of New York, have invented certain new and useful Improvements in Rotary Explosion-Engines, of which the following is a specification.

This invention relates to explosion engines and more particularly to engines of the rotary type.

One object resides in the provision of an explosion engine embodying a casing provided with an explosion chamber in which 15 is rotatably mounted a piston carrier provided with pistons in combination with a means arranged within the casing of the engine for forming and compressing an explosive fluid with a valved passage between 20 the fluid forming and compressing means and the explosion chamber so as to regulate the supply of fluid to the forming and compressing means and of the compressed fluid from the forming and compressing 25 means to the explosion chamber.

Another object is to provide a rotary explosion engine having a rotatable piston carrier and a fluid forming and compressing means which is operable under the influence of the rotatable piston carrier and 30 which is arranged within the explosion chamber so that the heat units of the latter are utilized to bring the fluid to a proper degree of efficiency to effect a perfect combustible explosive fluid with a valve to provide for a charging of the forming and compressing means and to effect a transfer of the compressed fluid from the forming and compressing means to the explosion 35 chamber of the engine where it is exploded to drive the rotatable member.

Another object is to provide a rotary explosion engine including a casing having an explosion chamber and a rotatable piston 45 carrier mounted therein with an internal fluid forming and compressing means between which and the explosion chamber and confined within the rotatable piston carrier there is disposed means to simultaneously 50 control the supply of fluid to the forming and compressing means and also to effect a transfer of the compressed fluid from the forming and compressing means to the explosion chamber where it is exploded to 55 drive the rotatable member.

Another object is to provide a rotary explosion engine embodying a casing having an explosion chamber in which is mounted a rotatable member provided with pistons adapted to slide radially thereof and also 60 provided with fluid forming and compressing chambers in which are mounted reciprocating plungers, means for connecting the pistons so that one will counterbalance the other with means connecting the plungers 65 so that one plunger will counterbalance the other and with the connecting means between the plungers and the pistons operatively connected together.

Another object resides in the provision 70 of a rotary explosion engine having an explosion chamber therein in which is mounted a rotatable piston carrier in which latter is located means for forming and compressing the fluid for explosion in the 75 explosion chamber to drive the rotatable member, the forming and compressing means including plungers confined within the rotatable member and thereby shielded from the direct heat and explosion of the 80 gases in the explosion chamber of engine.

Another object is to provide a rotary explosion engine having an explosion chamber in which is mounted a rotatable piston carrier and a fluid forming and compressing means which is operable under the influence of the rotatable piston carrier and 85 which has communication with the explosion chamber of the engine through suitable controlling means adapted to govern 90 the supply of the fluid to the forming and compressing means and also to control the supply of the compressed fluid from the forming and compressing means to the explosion 95 chamber.

A still further object is to provide a rotary explosion engine including a casing having an explosion chamber therein in which is mounted a rotatable piston carrier and also a fluid forming and compressing 100 means consisting preferably of oppositely disposed fluid compressing chambers in each of which are plungers suitably connected together to reciprocate them in the compressing chambers with means arranged 105 to effect a charging of one compressing chamber under the suction stroke of its plunger and simultaneously transfer the fluid under the compression stroke of the plunger of the other compressing chamber 110.

to the explosion chamber where it is exploded to drive the rotatable member.

It is still further designed to provide a rotary explosion engine having an explosion chamber and a rotatable piston carrier mounted therein with fluid forming and compressing means confined within the explosion chamber and including plungers connected together so that one plunger counterbalances the other.

With the above and other objects the present invention consists in the combination and arrangement of parts hereinafter more fully described, illustrated in the accompanying drawings and particularly pointed out in the appended claims, it being understood that changes may be made in the form, proportion, size and minor details without departing from the spirit or sacrificing any of the advantages of the invention.

In the drawings:—Figure 1 is a longitudinal sectional view of the invention. Fig. 2 is a transverse sectional view on the line *a—a* of Fig. 1. Fig. 3 is a horizontal sectional view. Fig. 4 is a transverse sectional view on the line *b—b* of Fig. 1. Fig. 5 is a transverse sectional view of the invention illustrating the fluid compression means in action to receive a supply of fluid for compression and also transferring compressed fluid to the explosion chamber. Fig. 6 is a detailed view showing parts of the fluid forming and compressing valve controlling means. Fig. 7 is a perspective view of the abutment. Fig. 8 is a perspective view of one of the end caps which telescope the abutment. Figs. 9, 10, 11 and 12 are perspective views of the compensating rings for counterbalancing the pistons and the plungers of the fluid forming and compressing means. Fig. 13 is a perspective view of the piston carrier illustrating the telescoping end caps applied thereto and with the compensating ring shown ready for connection with the pistons and the plungers. Fig. 14 is a fragmentary view of the piston carrier illustrating one of the friction reducing members carried at the ends of the pistons. Fig. 15 is a detailed perspective view of one of the friction reducing members carried by the pistons.

Referring now more particularly to the accompanying drawings the casing or frame of my improved engine consists of a suitable supporting base 10 on which is mounted a cylinder 11 against the inner face 12 of which is disposed the abutment 13.

At each end of the cylinder are suitable end plates 14. These plates are preferably bolted to the end walls of the cylinder and are provided with central openings in which are located bearings 15 in which

65 rotates the main drive shaft 16 which latter

is preferably hollow throughout a portion of its length for a purpose presently explained.

Suitable packing and glands may be used for the main shaft. Said end plates on their inner faces are cut away so as to form a recess in which are located operating mechanisms for the radial pistons of the piston carrier and the plungers of the compressing mechanism, which will be herein-after more fully described.

The abutment 13 is formed with a cylindrical chamber 17 which is eccentrically disposed in the abutment so that said abutment is in effect cam shaped in cross section. In this chamber 17 is disposed a piston carrier 18 which is so proportioned as to engage the wall of the cylindrical chamber 17 at the point 19. The radial pistons are indicated at 20 and 21 and are so proportioned as to be held continually in contact with the wall of the cylindrical chamber 17 as the piston carrier rotates.

The abutment is formed on its outer face with a centrally disposed circumferential rib 22 which fits snugly within the cylinder 12 so that any lateral thrust against the abutment will be imparted through said rib to the supporting cylinder of the engine. This rib 21 forms at each end of the abutment cut-away portions adapted to receive the caps 23. These caps 23 are carried by the rotatable piston carrier by means of suitable fastenings 24, if not cast therewith.

The outer face of the abutment on opposite sides of said ribs is still further cut-away so as to form a series of chambers 25 which are circumferentially arranged about the abutment and extend from a point adjacent the center rib 21 to the ends of the abutment. These chambers are separated by ribs 26 extending longitudinally of the abutment. Each cap 23 has a shoulder 23' adapted to close the outer ends of the chambers 25 and the caps are so proportioned as to have a smooth running fit with the ribs 26. Each chamber 25 is connected with the cylindrical chamber 17 by a port 27.

The combined area of the chambers 25 in the outer surface of the abutment is substantially the same as the area of the outer surface of the rotating piston carrier. As the piston carrier rotates the radial piston 12 will uncover one port 27 after another so that the surface on the rotating carrier exposed to pressure is kept substantially equal to the surface on the caps 23 covering the chambers 25 which are exposed to the same forces of pressure. The result is that inasmuch as these pressure forces are opposed to each other, the one will counterbalance the other and therefore all the objectionable lateral strains on the piston carrier are neu-

tralized so that the carrier will rotate freely on its bearings regardless of the pressure loads in the expansion or explosion chamber 17. By virtue of this counterbalancing action the carrier runs smoothly without vibration or chatter even though the carrier be off center.

The piston carrier 18 is rigidly connected with the main shaft 16, as above stated, and is so proportioned as to have a smooth running contact with the wall of the cylindrical chamber 17 in the abutment 13. This wall of the abutment at the point of contact between the carrier and the abutment may be provided with a plurality of slots 29 through which lubricant may be inserted so as to fill the chambers 25 with the lubricant to provide for a smooth running joint connection between the aforesaid caps and the abutment. These slots are covered by the rotatable carrier because of the running fit of the carrier with the abutment at this point.

The piston carrier is formed with oppositely disposed radial grooves 30 in which are mounted the radial pistons 20 and 21. Each end of the piston carrier 18 is provided with a flange or annular plate 31. The inner faces of these plates 31 form walls which together with the outer surface of the piston and the inner surface of the cylindrical chamber in the abutment and a portion of the abutment intermediate its ends form the explosion chamber 17 of the engine. These end plates 31 are formed with radial grooves 32 which are similar to the radial grooves 30 in the piston carrier. The radial pistons extend into the radial grooves or guideways 32 in the end plates 31. Mounted on each end of each radial piston is a plate 33 each provided with a slot 34 which embraces the piston and with lugs 35 adapted to engage the inner and outer edges of the pistons. On each side 45 edge of each plate 33 is a grooved guideway 36 in which roller or other bearings 37 are guided and which are adapted to bear and roll against the shoulders 38 formed by milling the outer sides of the 50 plates 31 adjacent the guide-ways 30. These plates 33 with their rollers are so disposed as to take up side thrust against the radial pistons and to provide for a free easy movement of the pistons 20 and 21 in their radial 55 movement relative to the piston carrier. The end plates 31 may be made solid or they may be cut away centrally thereof to lighten the same, the essential features being the outer smooth circumferential surface which 60 fits snugly within the balancing caps 23 and the inner flat walls which form the end walls of the explosion chamber. One of these end plates may be made integral if desired with the piston carrier while the 65 other is detachable or both may be made de-

tachable from the piston carrier. The end thrust on the carrier due to the expansion of the gases in the chamber 17 will be perfectly counterbalanced because the forces acting on end plate 31 at one end of the 70 carrier will be overcome by the thrust acting on the end plate 31 at the other end of the carrier.

The inner edges of the caps are formed preferably with an annular rib 39 which engages the annular grooves 40 in the side edges of the aforesaid central rib 22 on the outer side of the abutment. This rib and groove connection between the central rib 22 and the caps 23 prevents leakage from 75 the chambers 25 about the inner ends of the caps. The abutment 22 may also be provided, if desired, with headed pins 41 which are spring pressed outward against the end plates 31 and these headed plates serve as 80 85 wearing surfaces.

The end caps are slotted as at 42 and each radial piston is formed with a connecting stem 43 which is preferably rectangular in cross section and each stem fits in a bearing 90 block 44 mounted in the respective compensating ring for the radial piston. One of the radial pistons is connected to a compensating ring 45 through the projecting lug 46 which carries the bearing 44. This ring 95 45 is adapted to fit a hub or bearing 47 arranged on one of the end plates 14 centrally of the bore of the cylinder and concentrically of the main shaft. Said hub or bearing, however, is eccentric to the piston carrier 100 and radial pistons so that as said carrier rotates the radial pistons will be moved relatively to the carrier. There is a compensating ring 45 at each end of the piston carrier. The eccentric bearing 47 may have a 105 race-way 48 formed therein in which is located a series of roller or other bearings 49 to take up any wear between the ring and the eccentric hub 47. The oppositely disposed radial pistons are connected to compensating rings 50 which have projecting lugs 51 carrying bearings 44. These rings 50 engage a flange 52 carried by the rings 45. Said rings 50 may have formed therem a race-way 53 in which is placed a series 110 of roller bearings 54 so that any wear between the rings and the flanges will be taken by the supporting roller bearings. By this construction of the rings whereby one ring of each set is connected to the other and 115 both rings of each set connected to the corresponding eccentric hub, I have provided a construction which will operate to hold the radial pistons in proper running contact with the wall of the cylindrical chamber 19 120 and at the same time one radial piston will counterbalance the other. The centrifugal force acting upon one radial piston will, through the collar 52, be opposed by a substantially equal centrifugal force acting on 130

the other radial piston; these forces being opposed counterbalance each other as above noted.

The outer edges of the radial pistons may be provided with longitudinal grooves in which may be mounted packing strips 55 which are yieldingly forced outward against the wall of the abutment by springs 56. These packing strips 55 are relatively light and the centrifugal force acting thereon will merely hold the same in smooth running contact with the wall of the chamber 17.

By the above construction it will be apparent that I have provided a piston carrier 15 with radial pistons which are so operated as to be held in smooth running contact with the wall of the explosion chamber, and regardless of the speed of the engine, said radial pistons will be properly counterbalanced one by the other so that all friction and undue wear between the radial pistons and the wall of the cylinder are avoided.

In the rotatable piston carrier 18 there is formed oppositely disposed compression chambers 57 and 58 which chambers extend throughout the length of the rotatable carrier and which are formed open ended therein but which are closed by the end plates 14. In each compression chamber 80 57-58 is a plunger 59 which extends throughout the length of the corresponding chamber and each of which has metallic or other packing strips 60 in its opposite side faces which engage the sides of the chamber. These plungers 59 are adapted to move inwardly and outwardly alternately during rotation of the piston carrier 18 and they are counterbalanced one by the other as are the pistons 20-21. One way to counterbalance the plungers 59 is to provide the outer face of each with a T-shaped slot 61 which is open ended and into each of which slots 61 is loosely positioned a T-bar 62. These T-bars 62 extend through slots 63 in the caps 45 with their extremities fitted in bearings 44 in lugs 63 and 64 respectively, of compensating rings 65 and 66 which latter are mounted on the aforesaid compensating rings 45 with roller bearings preferably between them and the rings 45. By thus connecting the plungers 59 with the compensating rings they are caused to slide in their respective chambers 57 with one plunger moving outwardly while the other is moving inwardly. Both plungers are so connected that they travel in a true circle and within the true circle in which the pistons 20-21 travel. Furthermore, by having the plungers 59 and the pistons 20-21 mounted 60 from the same center, that is on the hubs 47 of the end plates 14, with the compensating rings of the plungers having oscillatory movement with relation to each other at each end of the engine as have the compensating rings of the pistons at each end of

the engine, the plungers and the pistons are connected together.

The fluids for compression and subsequent transfer into the explosion chamber for explosion to drive the rotatable member 70 are mixed proportionably automatically in a mixing device consisting of a casing 68 which is preferably bolted to the arm 69 secured by means of bolts 70 or otherwise to one of the end plates 14 of the gasoline chamber 72 and an air chamber 73 and has a series of ports 74 which gradually increase in size and which establish communication between the gasoline and the air chambers. The casing 68 of the mixing device is provided with an opening which forms a valve seat on which is normally seated a valve 75, there being a spring 76 arranged between the shoulders 77 on the casing 68 and a collar 78 on the stem 79 of the valve 75 to hold the latter normally seated. The stem 79 of said valve extends through the outer end of the casing 68. A piston valve 80 is slidably mounted through the outer end of the casing 68 and has a series of ports 80' 90 therein which gradually increase in size. The piston valve 80 and the stem 79 are preferably adjustably connected together by a link 81 with the result that when the valve 75 is unseated against the tension of the spring 76 in a manner to be hereinafter explained, the piston valve 80 is moved inwardly accordingly so that the amount of gasoline permitted to pass into the air chamber from the gasoline chamber is regulated to the extent that there is a proportionate amount of gasoline supplied to the air chamber for mixture with the air. The quantity of air entering the air chamber of the mixing device is controlled preferably by a butterfly valve 82 and the gasoline is supplied to the gasoline chamber 80 by means of a pipe or the like 83.

To provide for the control of the mixed fluid from the mixing device to the compression chambers and subsequent compression of the fluid and transfer thereof into the explosion chamber, I provide a single valve which may be constructed by providing the hollow portion of the main drive 110 shaft 16 with upper and lower ports 87 and 88 which are adapted to rotate into and out of registration with the recess 85 in the valve member 84. The hollow portion of the main drive shaft 16 has other upper 115 and lower ports 89 and 90 which are adapted to be rotated into and out of registration with the port 86 in the valve member 84 as the shaft and rotatable carrier 18 rotate so as to provide for the supply of the fluid 120 to the compression chambers. For instance, referring to Fig. 4 and assuming that the rotatable member 18 is in rotation, the plunger 59 in the compression chamber 58 is 125 compressing fluid, and forcing it through 130

the port 88 and into the recess 85 and the duct 91 which is at this time in communication with the recess 85 and when, as shown in Fig. 2, the port 88 has passed beyond the recess 85 the duct 91 and port 88 are no longer in communication with the recess 85. The fluid has been compressed and has been forced into the explosion chamber 17 in the rear of the piston 21 when it is exploded by means of an ordinary spark plug 92 connected up in any suitable manner with any suitable source of electric energy as will be explained more in detail hereinafter. The explosion of the charge of compressed fluid expanding and impinging against the piston 21 furnishes the force or impulse to rotate the rotatable member. The products of combustion pass out of the explosion chamber 17 through the exhaust chamber 20 when the pistons pass the exhaust chamber 93 and exhaust port 94. When the port 88 passes the recess 85 the port 90 in the shaft 16 registers with the port 86 in the fixed valve member 84 so that as the plunger in 25 the compression chamber 58 moves outwardly there is created a vacuum or suction which draws in an additional charge of fluids from the mixing device by way of the hollow valve member 84 and ports 90 and 86 into the chamber 58. By the time that the compression chamber 58 has reached the position occupied in Fig. 2 by the chamber 57, its plunger 59 has reached its outermost movement and the port 90 of 30 the main drive shaft 16 has passed the port 86 in the valve member 84 thereby cutting off supply to the compression chamber 57. The continued rotation of the rotatable member 18 brings the ports 87-87' and 35 duct 95 into registration with the recess 85 as were the ports 88-88' and the duct 91 in Fig. 4 and by the time the duct 95 crosses entirely over the recess 85 a compressed charge has been supplied to the explosion chamber 17 by way of said duct 95 for the explosion. The ports 87' and 88' are always in registration with the ducts 91 and 95 respectively because of the rotatable member being fixed to the main drive shaft. I thus 40 supply a plurality of compressed charges to the explosion chamber on each rotation of the rotatable member, alternately forming charges and supplying the formed charges to the explosion chamber, all 45 through a single valve having one fixed and one movable port.

When it is desired to start the engine a certain amount of compressed gases may be led directly to the combustion or explosion chamber 17 through a hollow supply port 96 or a certain amount of explosive fluid may be supplied to the combustion or explosion chamber 17 and compressed therein by an ordinary hand pump (not shown) 50 through this hollow port 96. To explode

this initial charge as well as the regular charges I have provided the engine with the aforesaid ordinary spark plug 92 and this spark plug may be connected up with a source of electric energy shown as a storage 70 battery 97 by means of a wire 104, there being a metallic ring 98 secured fixedly to the main drive shaft 16 and insulated therefrom by a fibrous ring 99, the metallic ring having contacts 100 and 101 adapted to rotate into engagement with the contact 102 secured to and insulated from the bracket arm 69 with which a wire 103 connects it with one pole of the spark plug 92. One pole of the battery is connected by a wire 80 104 to the spark plug 92 with a wire 105 leading to the wire 106 to which is electrically connected a brush 107 engaging at all times the aforesaid annular ring 99. When the contacts 100 and 101 separately contact 85 with the single contact 102 a spark is made from the spark plug 92 through said battery wires and brush behind the corresponding piston 20-21, there being as many contacts on the ring 99 as there are pistons carried by the piston carrier with a switch 108 in the wire 104 to make and break the circuit when desired. Any other electrical connections for the spark plug may be employed.

In order to properly cool the various parts of the engine I have provided the same with a water jacket 109 in which there is an opening 110 through which water may be supplied and caused to circulate up over the top of the engine with an outlet 111 for drawing over any water that may remain at the top of the engine when it is desired to remove water from the jacket 109. This jacket or chamber 109 in the abutment extends throughout the center circumferential rib and also extends laterally into the end sections of the abutment. The water in this chamber will effectively cool the inner wall of the abutment forming the cylindrical 110 chamber in which the piston carrier rotates.

To effectively cool the rotary piston carrier I may form a duct 112 in the drive shaft 16 and provide branch pipes 113 which communicate with the duct 112 for conveying water into the chambers 114 of the piston carrier. At the outer end of the shaft the duct 112 may be closed as is obvious. As a matter of fact, the water in the chambers 120 would be confined therein incident to centrifugal force. By this arrangement I am able to keep the rotary piston carrier and the compression chamber cool.

To prevent burning of oils and gases and consequent smoking and undue heating of the engine by burning oils and gases, I preferably dispose in each port 27, leading from the combustion chamber to the lubricant chambers 25 a spring controlled ball valve 130

with a ball 115 held normally against the shoulders 116 adjacent the inner ends of the ports by the springs 117 supported by the ported plugs or bushings 118. These spring controlled ball valves prevent the gases from passing into the chambers 25 and they seal the latter against loss of lubricant back into the explosion chamber so that there is always confined in the chambers 25 and also in the ports 27 a full supply of lubricant. In other words, these spring controlled valves prevent the lubrication from coming back into the cylinder 17 and also prevent leakage. I therefore provide a perfect seal so that gases will not pass through the ports 27. The springs 117 are constantly in a bath of lubricant and consequently not affected by heat.

The lubricant is preferably applied to the chambers 25 by one of the aforesaid slots or openings 29 formed through the lower side of the abutment. These slots or openings are maintained closed because of the rotatable piston carrier 18 operating against the wall of the explosion chamber directly over the same as has been stated. By this method of supplying the lubricant and maintaining the chambers 25 and the ports 27 full of the lubricant, the lubrication necessary is practically inexpensive.

From the foregoing it will be understood that pistons 20 and 21 are counterbalanced one by the other and that the plungers 58 and 59 are also counterbalanced one by the other. The plungers are guided and supported by compensating rings of the same form and construction as the compensating rings by which the pistons are guided and supported and by virtue of the compensating rings of both the plungers and the pistons being operatively connected together and mounted on the same centers, there is coöperation between the plungers and the pistons and an even and positive operation of one plunger with relation to the other and of one piston with relation to the other with the compensating rings of the plungers having oscillatory movement on each other and the piston compensating rings having oscillatory movement one on the other. It will also be seen that by means of a single valve consisting of a fixed and a movable element I am enabled to control the admixture of the fluids and the compression thereof and transfer of the same to the explosion chamber to operate the engine.

What is claimed is:

1. An explosive engine including in combination, a casing having a cylindrical chamber therein, a rotatable member in said chamber, oppositely disposed radial pistons carried by said rotatable member, oppositely disposed compression means carried by said rotatable member and each including a chamber and a plunger, means operatively

connecting said plungers together whereby, upon rotation of the rotatable member the plungers are operated to compress the fluids on their inward strokes in said chambers alternately and to transfer the compressed fluid to said cylindrical chamber, and means for exploding the fluid in the cylindrical chamber, to drive the rotatable member.

2. An explosive engine including in combination, a casing having a cylindrical chamber therein, a rotatable member in said casing, oppositely disposed radial pistons carried by said rotatable member, means connecting said pistons so that one piston is counterbalanced against centrifugal action by the other piston, oppositely disposed fluid compressing means carried by said rotatable member and each including a plunger, means operatively connecting said plungers so that one plunger counterbalances the other and whereby, upon rotation of the rotatable member, the plungers are operated to compress the fluid and to deliver the compressed fluid to said cylindrical chamber, and means for exploding the fluid to drive the rotatable member.

3. In a rotary explosive engine, including in combination, a casing having a cylindrical chamber therein, a rotatable member in said chamber, pistons carried by said rotatable member, compressing means carried by said rotatable member, means connecting said pistons operatively together, and means connecting said plungers operatively together and means whereby the connecting means of the plungers and the connecting means of the pistons are operatively connected together.

4. In a rotary explosive engine including in combination, a casing having a cylindrical chamber therein, a rotatable casing in the explosion chamber and having oppositely disposed compression chambers, plungers mounted in said compression chambers, means connecting said plungers operatively together, oppositely disposed pistons carried by the rotatable member, means operatively connecting the pistons together, and means whereby the connecting means between the pistons and the connecting means between the plungers may be mounted on the same centers to rotate with the rotatable carrier.

5. In a rotary explosive engine including in combination, a casing having a cylindrical chamber therein, a rotatable member in the explosion chamber and having oppositely disposed compression chambers, plungers mounted in said compression chambers, means connecting said plungers operatively together, oppositely disposed pistons carried by the rotatable member, means operatively connecting the pistons together, and means whereby the connecting means between the pistons and the

- connecting means between the plungers may be mounted on the same centers to rotate with the rotatable carrier, with the pistons always traveling in a true circle and with the plungers always traveling in a true circle and within the true circle of travel of the pistons.
6. In a rotary explosive engine including in combination, a casing having a chamber therein, a drive shaft journaled through said chamber, a rotatable member in said chamber secured to said shaft, said shaft having a ported hollow portion, a fluid mixing device, a compressing means carried by the rotatable member and means mounted in the hollow portion of said drive shaft for coöperation with the latter as the latter rotates to effect operation of the mixing device by the compressing means and transfer the mixture from the compressing means into the explosion chamber to rotate the rotatable member.
7. An explosive engine including in combination, a casing having a chamber therein, a rotatable piston carrier located in said casing, a fluid mixing device located exteriorly of the engine casing, fluid compressing means located within said carrier and means located within the casing at the axis of the rotatable member to permit passage of fluids from the mixing device to the compressing means by suction in the latter and permit of a subsequent transfer of the compressed fluid from the compression means to the explosion chamber, and means for exploding the fluid in the explosion chamber to drive the rotatable member.
8. A rotary explosion engine including in combination, a casing having a chamber therein, a drive shaft journaled through said casing and having a hollow portion provided with ports, a fluid mixing device, fluid compression means within the rotatable member and having communication with the hollow portion of said shaft and operable within the latter to permit passage of the fluids from the mixing device to the compression means and to permit of a subsequent transfer of the fluid from the compression means to said chamber, and means for exploding the fluid in the chamber to drive the rotatable member.
9. An explosion engine including in combination, a casing having a chamber therein, a rotatable piston carrier in the chamber, a fluid mixing device, spaced alining fluid compression chambers within the carrier, plungers mounted within the compression chambers, means operatively connecting the plungers together and arranged to rotate with the piston carrier and means to permit passage of the fluid from the mixing device to the compression chambers by suction in the latter and permit of a subsequent transfer of the compressed fluid from the compression chambers to the first named chamber, and means to explode the fluid in the first named chamber to drive the rotatable member.
10. A rotary explosive engine including in combination a casing having a chamber therein, a rotatable piston carrier located in said chamber, a fluid mixing device, fluid compression chambers within the carrier, plungers mounted in the compression chambers, means operatively connecting the plungers together and arranged to rotate with the piston carrier, and a single valve located within the chamber and operable under the influence of rotation of the rotatable member to permit passage of the fluids from the mixing device to the compressing means by suction in the latter and permit of a subsequent transfer of the compressed fluid from the compression chambers to said chamber, and means for exploding the fluid in said chamber between the walls of the latter and the carrier to drive the latter.
11. A rotary explosive engine including in combination, a casing having a chamber therein, a rotatable piston carrier located in said chamber, a fluid mixing device, fluid compression chambers within the carrier, plungers mounted in the compression chambers, means operatively connecting the plungers together and arranged to rotate with the piston carrier, a valve located within the chamber and consisting of a fixed and a movable part with the movable part operable under the influence of rotation of the rotatable member to permit passage of the fluids from the mixing device to the compression chambers by suction in the latter and permit of a subsequent transfer of the compressed fluid from the compression chambers to the aforesaid chamber, and means for exploding the fluid in said latter chamber to drive the rotatable member.
12. A rotary explosive engine including in combination a casing having a chamber therein, a rotatable piston carrier located in said chamber, a fluid mixing device, oppositely disposed fluid compression chambers arranged within the carrier, plungers mounted in said compression chambers, means connecting said plungers together so that they are moved inwardly and outwardly of the compression chambers and so that one counterbalances the other, and means located in the chamber and operable under the influence of rotation of the rotatable carrier to permit passage of the fluids from the mixing device to the compressing means by suction in the latter and permit of a subsequent transfer of the compressed fluid from the compression chambers alternately to the aforesaid chamber, and means for exploding the fluid in said latter chamber to drive the rotatable member.
13. An explosive engine including in com-

bination a casing having a chamber therein, a rotatable member in said chamber, oppositely disposed radial pistons carried by said rotatable member, oppositely disposed compression chambers carried by said rotatable member, a plunger mounted in each compression chamber, interengaging rings connecting the plungers at each end thereof, interengaging rings connecting the pistons at each end thereof, and means whereby the compression chambers are supplied with an operating fluid with the plungers operable to compress the fluid and through the aforesaid means permit deliverance of same to the chamber, and means for exploding the fluid in the cylindrical chamber to drive the rotatable member.

14. An explosive engine including in combination a casing having a chamber therein, a rotatable member in said chamber, an internal compressing means, and means consisting of a fixed member and a movable member arranged at the axis of the rotatable member to govern the charge of fluid to the compressing means and also the discharge of the compressed fluid from the compressing means.

15. An explosive engine including in combination, a casing having a chamber therein, a rotatable member in said chamber, an internal compressing means, and means consisting of a fixed member and a movable member arranged at the axis of the rotatable member to govern the charge of fluid to the compressing means and also the discharge of the compressed fluid from the compressing means, and a duct in the rotatable member leading from said means to said explosion chamber.

16. An explosive engine including in combination a casing having a chamber therein, a rotatable member in said chamber, oppositely disposed radial pistons carried by said rotatable member, means connecting the pistons together, an internal compressing means, unrestricted ducts formed in the rotatable member, one having its outlet in the rear of each piston, and means constructed and arranged to govern the charge of fluid to the compressing means and to effect a discharge of the compressed fluid from the compressing means to the explosion chamber through said ducts.

17. A rotary explosive engine including in combination, a casing having a cylindrical chamber therein, a rotatable member in said chamber, oppositely disposed radial pistons carried by said rotatable member, oppositely disposed compression chambers carried by said rotatable member and closed at their outer ends, fluid compressing means carried by the rotatable member to compress the fluids and supply said cylindrical chamber with the compressed explosive fluid, means for exploding the same, the compressing

means being confined within the rotatable member, and means for counterbalancing the varying lateral forces of the impact and the expanding gases on said rotatable member.

18. A rotary explosive engine including in combination, a casing having a cylindrical chamber therein, a rotatable member in said chamber, oppositely disposed radial pistons carried by said rotatable member, compressing means carried by the rotatable member and including a compression chamber closed at its outer end and a plunger, means whereby the fluid may be compressed in said compressing means and transferred to said cylindrical chamber, means for exploding the fluid, and means for utilizing a portion of the impact and the expanding forces for creating an opposing force on the rotatable member substantially equal to the lateral impact and the lateral forces of the expanding gas on said rotatable member.

19. An explosive engine including in combination, a casing having a chamber therein, a rotatable member in said chamber, a compressing means in said rotatable member including a plunger operable under the influence of rotation of the rotatable member, and a valve arranged at the axis of the rotatable member and operating in unison with the plunger to effect a supply of mixed fluids to the compressing means on the suction stroke of the plunger and a discharge of the compressed fluids from the compressing means into the chamber on the compression stroke of the plunger, and means for exploding the same.

20. An explosive engine including in combination, a casing having a chamber therein, a rotatable member in said chamber, spaced, alining fluid compression chambers carried by the rotatable member, a plunger in each compression chamber, means connecting the plungers and rotatable with the rotatable member to operate the plungers, and means operating in unison with the plungers to effect a supply of mixed fluids to the compression chamber on the suction stroke thereof and a subsequent discharge of the compressed fluids from the compression chambers on the compression strokes of the plungers to deliver the compressed fluids to the explosion chamber and means for exploding the same.

21. An explosive engine including in combination, a casing having a chamber therein, a rotatable member in said chamber, spaced, alining fluid compression chambers carried by the rotatable member, a plunger in each compression chamber, means connecting the plungers and rotatable with the rotatable member to operate the plungers, and means operating in unison with the plungers to effect a supply of mixed fluids to the compression chamber on the suction stroke thereof and a subsequent discharge

of the compressed fluids from the compression chambers on the compression strokes of the plungers to deliver the compressed fluids to the explosion chamber, and means for exploding the same, one plunger operating on the suction stroke while the other plunger is operating on the compression stroke.

22. A rotary engine of the character described, including in combination, a casing having a chamber therein, a shaft journaled through the casing and having a hollow portion, a rotatable member secured to said shaft, compression chambers carried by the rotatable member and having communication with the hollow portion of said shaft, plungers mounted in said compression chambers and operable therein under the influence of rotation of the rotatable member to form and compress an explosive fluid, and means cooperating with the communication between the chambers and hollow portion of said shaft to open and close the communication between the shaft and the compression chambers and to permit a discharge of the compressed fluid from the compression chamber into said first named chamber, and means for exploding the explosive fluid in the latter chamber.

23. An explosive engine including in combination, a casing having a chamber therein, a rotatable member in said chamber, a compressing means including oppositely disposed alining chambers, a plunger in each compression chamber, means connecting the plungers and operable with the rotatable member to reciprocate the plungers, and passages between said compression chambers and operating in unison with the plungers to effect a supply of mixed fluids through one of the passages to the compression chambers on the suction stroke of the plungers and a subsequent discharge of the compressed fluid through the other passage on the compression stroke of the plungers to transfer the compressed fluid from the compression chambers to the explosion chamber, and means for exploding the fluid in the first named chamber.

24. An explosive engine including in combination, a casing having a cylindrical chamber therein, a rotatable member in said chamber, oppositely disposed spaced, alining compression chambers carried by said rotatable member and rotatable thereby, a plunger mounted in each compression chamber, means connecting the plungers together so that the plungers may be reciprocated and so that one plunger counterbalances the other, and means whereby compressed fluid may be transferred from each compression chamber under the compression stroke of the corresponding plunger to the cylindrical chamber, and means for exploding the fluid in the cylindrical chamber.

25. A rotary explosive engine including in

combination a casing, a rotatable piston carrier in the casing, a plurality of pistons carried by the rotatable member, means connecting the pistons together so that one piston will counterbalance the other against the centrifugal force incident to rotation of the rotatable member, a plurality of fluid compression chambers carried by the piston carrier, a plunger mounted in each compression chamber, and means connecting the plungers together so that one plunger will counterbalance the other.

26. A rotary explosive engine including in combination a casing, a rotatable piston carrier in the casing, a plurality of pistons carried by the rotatable member, means connecting the pistons together so that one piston will counterbalance the other against the centrifugal force incident to rotation of the rotatable member, a plurality of fluid compression chambers carried by the piston carrier, a plunger mounted in each compression chamber, means connecting the plungers together so that one plunger will counterbalance the other, and means operable with the plungers to supply the compression chambers with fluid on the suction stroke of the plungers and to effect a transfer of the compressed fluid on the compression stroke of the plungers from the compression chambers to the explosion chamber, and means for exploding the compressed fluid in the explosion chamber to rotate the rotatable member.

27. A rotary explosive engine including in combination, a casing, a rotatable piston carrier in the casing, a plurality of pistons carried by the rotatable member, means connecting the pistons together so that one piston will counterbalance the other against the centrifugal force incident to rotation of the rotatable member, a plurality of fluid compression chambers carried by the piston carrier, a plunger mounted in each compression chamber, and means connecting the plungers together so that one plunger will counterbalance the other, the connecting means of the pistons having inter-engaging connection with the connecting means between the plungers.

28. A rotary explosive engine including in combination, a casing, a rotatable piston carrier in the casing, a plurality of pistons carried by the rotatable piston carrier, sets of inter-engaging rings connecting the ends of the pistons, a plurality of fluid compression chambers carried by the piston carrier, a plunger mounted in each compression chamber, sets of inter-engaging rings connecting the plungers and inter-engaging with the sets of rings which connect the pistons, said rings operating under the influence of the rotatable member to operate the pistons and the plungers, a fluid mixing device, and means between the fluid mixing device and the compression chambers to effect

- 5 a supply of mixed fluids to the compression chambers on the suction stroke of the plungers and effect a discharge of the compressed fluids on the compression stroke of the plungers to transfer the compressed fluids to the explosion chamber, and means for exploding the compressed fluids in the explosion chamber.
- 10 29. A rotary explosive engine including in combination a casing, a rotatable piston carrier in the casing, a plurality of pistons carried by the rotatable piston carrier, sets of interengaging rings connecting the ends of the pistons, a plurality of fluid compression chambers carried by the piston carrier, a plunger mounted in each compression chamber, sets of inter-engaging rings connecting the plungers and inter-engaging with the sets of rings which connect the pistons, said 15 rings operating under the influence of the rotatable member to operate the pistons and the plungers, a fluid mixing device, and valved passages between the compression chambers and the explosion chambers and operating with the plungers to effect a supply 20 of mixed fluids to the compression chambers on the suction stroke of the plungers and to effect a discharge of the compressed fluids on the compression stroke of the plungers to transfer the compressed fluid to the explosion chamber, and means for exploding the fluid in the explosion chamber.
- 25 30. A rotary explosive engine including in combination, a casing having a cylindrical chamber therein, a rotatable piston carrier mounted in the casing, a plurality of sliding pistons supported by the carrier, a fluid compression means confined within the rotatable member including chambers spaced 30 from the pistons and operable under the influence of the latter to supply compressed fluid to the cylindrical chamber, and means located within the carrier to control the supply of compressed fluid to the cylindrical 35 chamber.
- 35 31. A rotary explosive engine including in combination, a casing having a cylindrical chamber therein, a rotatable piston carrier mounted in the chamber, a fluid compression means including separate chambers confined 40 within the rotatable member and operable under the influence of the latter to supply compressed fluid to the cylindrical chamber, said separate compression chambers being 45 arranged in alignment with their inner ends relatively close, and a valve interposed between the inner ends of the separate chambers of the compressing means to control the supply of compressed fluid to the cylindrical 50 chamber.
- 55 32. A rotary explosive engine including in combination, a casing having a cylindrical chamber therein, a rotatable piston carrier mounted in the casing, oppositely disposed fluid compression chambers con- 55 fined within the rotatable member, plungers mounted in the fluid compressing chambers, means operatively connecting the plungers together, the compression chambers having communication with the cylindrical chamber, and means interposed between the fluid compressing chambers and located in the communication between the compression chambers and the cylindrical chamber to govern the supply of fluid to the compression chambers and also to govern the supply of fluid through said communication from the compression chambers to the cylindrical chamber.
- 60 33. A rotary explosive engine including in combination, a casing having a cylindrical chamber therein, a rotatable piston carrier mounted in the cylindrical chamber, oppositely disposed fluid compressing chambers confined within the rotatable member, 70 plungers mounted in the fluid compressing chambers, means operatively connecting the plungers together, the compression chambers having communication with the cylindrical chamber, and a valve interposed between the fluid compressing chambers and located in the communication between the compression chambers and the cylindrical chamber to govern the supply of fluid to the compression chambers and also to govern the supply of fluid through said communication from the compression chambers to the cylindrical chamber.
- 65 34. A rotary explosive engine including in combination, a casing having a cylindrical chamber therein, a rotatable piston carrier in the casing, radial pistons supported by the carrier, a fluid compressing means in the carrier spaced from the pistons and operable under the influence of the rotatable piston carrier, and means confined 80 within the carrier to alternately cut off and establish communication between the fluid compressing means and the cylindrical chamber.
- 70 35. A rotary explosive engine including in combination, a casing having a cylindrical chamber therein, a rotatable piston carrier in the casing, pistons slidably supported by the carrier, oppositely disposed fluid compressing chambers within the casing and spaced from the pistons, a plunger mounted in each compressing chamber and operable under the influence of rotation of the rotatable piston carrier, and means to 85 alternately establish communication between one compression chamber and the cylindrical chamber on the compression stroke of the plunger of said compression chamber and to cut off communication between the other compression chamber and the cylindrical chamber.
- 75 36. A rotary explosive engine including in combination, a casing having a cylindrical chamber therein, a rotatable piston car- 90

rier in the chamber, a fluid compressing means in the carrier and operable under the influence of the rotatable piston carrier, and a single valve including the axis of the rotatable member to alternately cut off and establish communication between the fluid compressing means and the cylindrical chamber.

37. A rotary explosive engine including in combination, a casing having a cylindrical chamber therein, a rotatable piston carrier in the chamber, oppositely disposed fluid compressing chambers within the casing, a plunger mounted in each compressing chamber and operable under the influence of rotation of the rotatable piston carrier, and a valve to alternately establish communication between one compression chamber and the cylindrical chamber on the compression stroke of the plunger of said compression chamber and to cut off communication between the other compression chamber and the cylindrical chamber.

38. A rotary explosive engine including in combination, a casing having a cylindrical chamber therein, a rotatable piston carrier in the casing, oppositely disposed fluid compressing chambers within the casing, a plunger mounted in each compressing chamber, means connecting the plungers to reciprocate them in their chambers, and means interposed between the compressing chambers and between the latter and the cylindrical chamber to effect charging of one compressing chamber and simultaneous transfer to the cylindrical chamber of the fluid under the compression stroke of the plunger of the other compressing chamber, and means for exploding the compressed fluid in the cylindrical chamber to drive the rotatable member.

39. A rotary explosive engine including in combination, a casing having a cylindrical chamber therein, a rotatable piston carrier in the casing, oppositely disposed fluid compressing chambers within the casing, a plunger mounted in each compressing chamber, means connecting the plungers to reciprocate them in their chambers, and a valve interposed between the compressing chambers and between the latter and the cylindrical chamber to effect charging of one compressing chamber and simultaneous transfer to the cylindrical chamber of the fluid under the compression stroke of the plunger of the other compressing chamber, and means for exploding the compressed fluid in the cylindrical chamber to drive the rotatable member.

40. A rotary explosive engine including in combination, a casing having a cylindrical chamber therein, a rotatable piston carrier in the chamber, a fluid compressing means carried by the rotatable member and operable under the influence of the latter and hav-

ing communication from its inner end with the cylindrical chamber, and means interposed between the inner end of the fluid compressing means and the cylindrical chamber to alternately open and close the communication between the fluid compressing means and the cylindrical chamber.

41. A rotary explosive engine, including in combination, a casing having a cylindrical chamber therein, a rotatable piston carrier in the chamber, pistons carried by the carrier, devices operatively connected to the pistons to hold the pistons in constant running joint with the wall of the explosion chamber, means for connecting said devices whereby one of the pistons counterbalances the other during all parts of the rotation of the carrier, oppositely disposed fluid compressing chambers carried by the rotatable member, a plunger mounted in each compressing chamber, devices operatively connected to the plungers to reciprocate the plungers, and means for connecting said reciprocating operating devices whereby one of the plungers counterbalances the other to effect an alternate compressing of the fluids in the compressing chambers.

42. A rotary explosive engine including in combination, a casing having a cylindrical chamber therein, a rotatable piston carrier in the chamber, pistons carried by the carrier, devices operatively connected to the pistons to hold the pistons in constant running joint with the wall of the explosion chamber, means for connecting said devices whereby one of the pistons counterbalances the other during all parts of the rotation of the carrier, oppositely disposed fluid compressing chambers carried by the rotatable member, a plunger mounted in each compressing chamber, devices operatively connected to the plungers to reciprocate the plungers, and means for connecting said reciprocating devices whereby one of the plungers counterbalances the other, and means to effect a charging of one compressing chamber and simultaneously transfer to the cylindrical chamber the fluid under the compression stroke of the plunger of the other compressing chamber, and means for exploding the compressed fluid in the explosion chamber to drive the rotatable member.

43. An explosive engine including in combination, a casing having a cylindrical chamber therein, a rotatable member in said chamber, an internal compressing means, and means consisting of a fixed member and a movable member arranged to govern the charge of fluid to the compressing means and also the discharge of the compressed fluid from the compressing means.

44. A rotary explosive engine including in combination, a casing having a cylindrical chamber therein, a rotatable piston carrier mounted in the chamber, pistons carried by

the rotatable member, a fluid compressing means carried by the rotatable member and including a plunger which is shielded within the carrier from the gases of the explosion chamber, and which is closed at its outer end, and a valved passage operating with the plunger so that fluid from the compressing means may be transferred from the inner end of the latter to the cylindrical

chamber on the compression stroke of the plunger, and means for exploding the fluid in the explosion chamber.

In testimony whereof I affix my signature in presence of two witnesses.

BENJAMIN F. AUGUSTINE.
